UNITED STATES PATENT OFFICE

JAMES E. BODEN AND ROY T. ORR, OF LA CROSSE, WISCONSIN, ASSIGNEES TO SILUNT-KADDI CORPORATION, OF LA CROSSE, WISCONSIN, A CORPORATION OF WISCONSIN

GOLF BAG

Application filed November 23, 1929. Serial No. 409,283.

The object of our invention is to provide simple and inexpensive means whereby a golf bag may be supported in an upright position so that the golf player may select a desired club without inconvenience and the services of a caddy will be rendered unnecessary. Golf bags as now generally made are not capable of standing upon their own bases and unless a player employs a caddy he must carry his bag from tee to tee. While he is making a shot, the bag is dropped to the ground and in taking up the bag he frequently loses sight of the ball so that ball is lost or considerable time is spent in locating the ball. The present invention provides means whereby a bag will stand upright upon its own base and the mentioned disadvantages and inconveniences are overcome. The invention is illustrated in the accompanying drawings and will be herein-after fully set forth.

In the drawings:

Figure 1 is a perspective view of a golf bag equipped with our invention,

Fig. 2 is an enlarged diametrical section of the bag-supporting means,

Fig. 3 is a bottom plan view,

Fig. 4 is a diametrical section showing a slight modification,

Fig. 5 is an elevation of another form of the invention,

Fig. 6 is a bottom plan view thereof, and Fig. 7 is a detail section.

The golf bag 1 may be constructed of any approved material and is reinforced at its lower end by a band 2 of metal or heavy leather in the usual manner. According to the present invention, there is provided an auxiliary base or cup 3 of metal which is of

proper diameter to fit closely around the reinforcing base or band 2 of the bag and extend across the bottom of the same so as to firmly support it when the bag is set on the ground. Depending from the bottom 5 of the auxiliary base or cup and preferably formed integral therewith are spurs or teeth 6 which are adapted to enter the ground and embed themselves therein and thereby firmly support the bag when it is not being carried. A

guard or cover 7 is provided around the lower

portion of the cup or auxiliary base so as to house the spurs 6 and thereby prevent the same piercing and tearing the clothes of the carrier or possibly causing injury to the carrier by scratching or cutting the skin. This cover or guard is a cup-like structure provided at intervals in its side with vertical slots 9, and these slots accommodate studs or screws 10 which serve as guides and stops to prevent tilting of the cover relative to the base and also to prevent the cover dropping from the base inasmuch as the upper ends of the slots will gravitate toward the guide studs and rest upon the same. To assure the descent of the cover as the bag is lifted from the ground, an expansion spring 11 is disposed within the cover below the bottom 5 of the supporting base, as shown clearly in Fig. 2. When the bag is set upright on the ground, the spring will yield to pressure exerted upon the bottom 5 through the bag or through the clubs contained therein so that the spurs 6 will pass through the slots 12 in the bottom of the guard and enter the ground in an obvious manner.

The structure just described and illustrated in Figs. 1, 2 and 3 is especially adapted for applying the invention to bags already in use. In applying the invention to bags in the course of manufacture, the spurs 13 are secured directly to the bottom of the reinforcing band 2, as shown in Fig. 4, by welding, riveting or otherwise intimately uniting the spurs to the band. The guard 14 is constructed in all essential respects the same as the guard 7 first described and is provided with the vertical slots 15 engaging guide studs and stops on the base of the bag, as will be understood. An expansion spring 16 is disposed within the guard so as to project the same when the bag is raised.

In Figs. 5, 6 and 7, the reference numerals 1 and 2 designate the golf bag and the bottom reinforcement, as before. Encircling the bottom of the bag is a metallic base member or shallow cup 17 to the under side of which, at its margin, are secured spaced depending spurs 18 and arranged in cooperating relation to each spur is a shoe or guard 19 which is carried by the outer free end of a leaf spring 100

20, the several springs being firmly secured at their inner ends to the base. The shoes have convex bottoms whereby they may rest upon the ground without injuring the sod, and 5 through each shoe extends an opening 21 to permit the adjacent spur to pass to and enter the ground, the shoes yielding to the pressure exerted thereon, as shown in Fig. 7. When the bag is lifted, the springs 20 swing the 10 shoes downward so that the points of the spurs cannot catch in and injure the clothing or the person of the user. The downward movement of the shoes is limited by chains or other elements 22 which are attached at their lower ends to the outer ends of the shoes and at their upper ends to the same screws or rivets 23 which secure the base to the bag.

In all forms of the invention, it will be noted the structure is very simple and inexpensive but efficient means is provided whereby the bag may stand upright upon its own base and the player will not have his attention drawn from the ball nor will it be necessary for him to stoop in order to lift the bag from the ground so that the location of the ball may be noted and loss of the ball, consequently, avoided.

Having thus described the invention, we claim:

- 30 1. Means for supporting a golf bag comprising a plurality of ground-penetrating elements, means for connecting said elements to the bottom of a golf bag, a guard arranged to house the ground-penetrating elements 35 when it is in projected position, yieldable means for maintaining the guard in projected position, and means for limiting the movement of the guard to projected position.
- 40 2. Means for supporting a golf bag comprising a plurality of ground-penetrating elements, means for mounting said elements upon the base of a golf bag, a cover for said elements normally housing the same and adapted to uncover the same when the bag 45 is deposited on the ground, an expansion spring housed within the cover between the same and the bottom of the golf bag, and means for limiting the downward movement of the cover under the influence of said spring.
- 50 3. Means for supporting a golf bag comprising a plurality of ground-penetrating elements, means for mounting said elements upon the bottom of a golf bag, a cover housing said elements and provided with slots through 55 which said elements may project, guide studs arranged above the lower ends of the ground-penetrating elements, the cover being provided with vertical slots in its side through which said guide elements pass, and an expansion spring housed within the cover between the bottom of the same and the bottom of the golf bag.
- 60 4. Means for supporting a golf bag comprising a plurality of ground-penetrating spurs on the bottom of the bag; guards yield-

ably mounted on the bottom of the bag and having openings through which the respectively adjacent spurs may pass, and means for limiting the downward movement of the guards.

5. Means for supporting a golf bag comprising a plurality of ground-penetrating spurs on the bottom of the bag, guards yieldably mounted on the bottom of the bag and having openings through which the respectively adjacent spurs may pass, and flexible connections between the bag and the guards.

6. Means for supporting a golf bag comprising a plurality of ground-penetrating spurs on the bottom of the bag, leaf springs on the bottom of the bag, and guards carried by the free ends of the springs to extend around the respective spurs and prevent contact with the points thereof.

In testimony wherof we affix our signatures.
